UNITED STATES PATENT OFFICE.

LEONARD S. HARRISON, OF NASHVILLE, OHIO.

AUXILIARY BARREL FOR GUNS.

SPECIFICATION forming part of Letters Patent No. 278,546, dated May 29, 1883.

Application filed February 5, 1883. (No model.)

To all whom it may concern:

Be it known that I, LEONARD S. HARRISON, a citizen of the United States of America, residing at Nashville, in the county of Holmes and State of Ohio, have invented certain new and useful Improvements in Auxiliary Barrels for Guns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to guns provided with replaceable auxiliary barrels, its object being to provide a shot-gun with an auxiliary rifle-barrel which may be adjusted inside of the shot-barrel in such manner that both barrels

20 may be used in connection with the same firing devices.

To this end the invention consists in certain novel constructions and combinations of devices, which will be hereinafter fully described, and pointed out in the appended claims.

In the accompanying drawings, Figure 1 is a top view of a shot-gun barrel having an auxiliary rifle-barrel arranged therein. Fig. 2 is a longitudinal section on line $x x$, Fig. 1. Fig. 3 is a top view of the rifle-barrel detached. Fig. 4 is a side elevation of the gun with stock attached. Fig. 5 is a top view of a gun provided with an auxiliary barrel according to a modification of my invention. Fig. 6 is a longitudinal section of the same on the line $y y$, Fig. 4, and Fig. 7 is a perspective view of the rifle-barrel and wedge detached and separated. Fig. 8 is a detail view illustrating the barrel and ramrod supporting rings.

40 Referring to Fig. 1, the letter A indicates the shot-gun barrel, and B its breech-pin, said barrel being constructed in the ordinary manner, except that around its muzzle is secured a band, C, having an inclined catch, c, projecting laterally therefrom and grooved longitudinally, said catch being intended to engage a spring-catch, C', which projects from a collar, d, secured around the muzzle of the rifle-barrel D, which is arranged inside of the shot-50 gun barrel, its touch-hole coinciding with the nipple-hole of said barrel, this collar d being

preferably squared or flattened to receive a suitable wrench, by means of which the inner barrel should be withdrawn. The breech portion of the inner barrel should be of a size to fit snugly within the breech portion of the outer barrel; but it may taper toward its muzzle, and is provided with a loose conical collar, F, on the inner side of the fixed collar d, with its small end inward, and adapted to enter the muzzle of the outer barrel. This collar F is grooved longitudinally in order to permit the escape of gases and hot air from between the two barrels, and it is also provided with a notch, f, for conveniently with- drawing it.

55 In Fig. 2 the position of the inner barrel within the outer barrel is clearly shown, its touch-hole c coinciding with the nipple-hole of the outer barrel. This touch-hole may be smooth, and the same cap-tube or firing-cylinder may be used for both barrels; or the said touch-hole may be screw-threaded to receive a long screw-nipple projecting from a cap-tube, and passing entirely through the nipple-hole 75 of the outer barrel. The inner barrel is provided with a breech-pin, p, as shown in the drawings; but this pin may be dispensed with, and the breech-pin of the outer barrel will serve for both.

80 On the under side of the outer barrel a socket is formed in the gun-stock to receive the breech of the rifle-barrel when not in use, as shown in dotted lines, and near the muzzle of the barrel is a hinged ring, i, which may be turned down to receive the forward end of the rifle-barrel, or swung up against the barrel out of the way when the rifle-barrel is in use. Within this ring is a smaller ring, r', hinged on the same pin, which may be turned down to receive the ramrod, the rear end of which will be inserted in the stock.

85 From the description now given, the manner of inserting and removing the inner barrel will be fully understood without further explanation. When it is inserted and secured the piece may be used as a rifle, and as a shot-gun when the inner barrel is removed.

90 Any suitable firing apparatus may be used in connection with my improvement, as will be readily perceived.

95 In Figs. 5, 6, and 7 is illustrated a modifica-

tion of my invention, adapting an auxiliary barrel to be applied to an ordinary choke-bore shotgun. The main difference between this modification consists in providing the inner barrel with a segmental wedge, which secures its breech in proper position within the breech of the outer barrel, though there are, besides, some variations of the devices for connecting the barrels together at their muzzles. In Figs. 5 and 6 the outer barrel, A', has a choke-bore, or one which grows gradually smaller in diameter toward the muzzle. The inner barrel, B', is straight for the main portion of its length; but at about one-sixth the distance from the breech, one-half of its circumference is gradually expanded, as shown at b², and this segmental portion of its circumference terminates at its opposite longitudinal edges in shoulders b³, between which is a straight portion of the barrel, forming a seat for a segmental wedge, W, which is provided with a stem, w, having a sufficient length to extend beyond the muzzle of the barrel when the wedge is on its seat. It is provided at its outer end with a thumb-piece, w', by which it may be operated. Suitable guides, v, are arranged on the barrel for the stem w, said guides being preferably dovetailed or undercut to retain the stem when the inner barrel is removed from the outer barrel.

Around the muzzle of the inner barrel is a fixed collar, K, from the inner edge of which, at intervals, project small pins k, which fit into sockets formed to receive them in the edge of the muzzle of the outer barrel, the inner barrel being thus maintained in a proper central position. From this collar also projects a spring-catch, C², arranged to engage with a suitably-shouldered notch, c², formed in the outer barrel, an inclined groove serving as a guide for the spring-catch. In the side of the collar is formed a guide-groove for the stem w.

To place the inner barrel in position for use, the wedge is first drawn outward until it strikes the guides v, being then upon the

smaller portion of the barrel. Said barrel is then 45 inserted in the outer barrel until the pins k enter their sockets and the spring-catch C² engages with its retaining-notch in the outer barrel. The touch-hole of the inner barrel will then be in line with the nipple-hole of the 50 outer barrel, and the stem w is then to be forced inward upon its seat, which is upon the under portion of the barrel, and it will force the inner barrel up snugly against the inner periphery of the outer barrel. To remove the 55 inner barrel the wedge is first drawn outward and the spring-catch C² disengaged from the outer barrel, when the whole may be brought out together.

Any suitable firing apparatus may be employed, and the devices for holding the auxiliary barrel and rammer may be the same as heretofore described.

I wish it to be understood that I do not confine myself to the precise construction or arrangement of devices shown in the drawings and heretofore particularly described, but may vary the same or substitute equivalents therefor in any manner conducive to the carrying out of the essential principles of my invention. 70

What I claim is—

1. The combination, with the inner and outer barrels, of a retaining-catch arranged upon the outer barrel, and a spring-catch secured to the inner barrel, near its muzzle, substantially as 75 described.

2. The combination, with the choke-bore outer barrel, and the inner barrel having the wedge-seat formed at its breech portion, of the wedge provided with a stem by which it may 80 be forced upon said seat, substantially as described.

In testimony whereof I affix my signature in presence of two witnesses.

LEONARD S. HARRISON.
